UNITED STATES PATENT OFFICE.

ANATOL DAVID ISKOLS, OF SCHENECTADY, NEW YORK.

REVERSIBLE SCREW-PROPELLER.

1,181,458.

Specification of Letters Patent.

Patented May 2, 1916.

Application filed June 5, 1915. Serial No. 32,446.

To all whom it may concern:

Be it known that I, ANATOL DAVID ISKOLS, a resident of the city of Schenectady, county of Schenectady, State of New York, have invented certain new and useful Improvements in Reversible Screw-Propellers, of which the following is a specification.

My invention relates to that type of screw propeller for marine propulsion in which the blades are so mounted that they can be turned on their axes for the purpose of reversing the direction of movement of the boat or vessel propelled thereby without reversing the driving engine.

Reversible screw propellers as now constructed have the blades pivotally secured at their bases only, with the result that the reaction of the water, (which can be considered as a single resulting force acting at the center of pressure of the blade with a lever arm equal to the distance of said center from the base) creates a bending moment which imposes a considerable stress on the pivot of each blade. For large propellers and large engine capacities these stresses rise to such magnitude as to prevent the use of such constructions as have heretofore been available. To meet the problem of reversing vessels provided with non-reversible engines, as turbines for example; the accepted practice has been to provide special reversing means, such as reversing turbines, the blades of the propeller being rigidly fastened to their supports and occupying unvarying positions thereon. Such an arrangement is not only open to many complications but also increases the cost of the installation.

My present invention has for its object to overcome the objections above noted and to provide a reversible propeller of improved construction which is capable of withstanding heavy stresses and hence is available for large as well as small engine capacities.

For a consideration of what I believe to be novel and my invention, attention is directed to the accompanying description and claims appended thereto.

In the accompanying drawing which is illustrative of my invention, Figure 1 is an axial section of a reversible propeller; Fig. 2 is a similar view of a modification showing an electric motor located within the hub of the propeller for turning the blades thereon, and Fig. 3 is a diagrammatic illustration of

a means for indicating the angular position of the blades.

1 indicates the hub of the propeller which is made hollow to receive certain operating parts as will appear later. It is mounted on the tail or propeller shaft 2 in any suitable way. As shown the rear end of the shaft is made conical and the hub is snugly fitted thereto and held in place by a feather 60 3 and nut 4, the latter being accessible when the cover or cap 5 is removed. The hub is provided with as many stands or pedestals 6 as there are blades. As shown the stands are formed integral with the hub as ordinarily this is the best construction, but under certain circumstances they may be made separable. The arrangement of these stands is important. Each extends outwardly to and preferably somewhat beyond 65 the center of pressure of the blade supported thereby. By the "center of pressure" is meant that point or region of the blade where the hydraulic pressure above and below it (considering a blade to be standing vertical) will be substantially balanced. The advantage of this over fastening the blade at its inner end or base resides in the fact that in the latter case the pivot is subjected not only to pressure and resulting friction but also to bending with the resulting 70 tendency to cramp and thus to destroy or to greatly interfere with the reversibility of the blade. In my improved construction the pivot of each blade when in action, is 75 balanced, being located right at the point of application of the resulting force and hence is subject only to pressure and resulting friction, which is naturally unavoidable, but which can easily be taken care of without interfering with the reversibility of the 80 blade.

Theoretically the bearing for the blade should be a point and register with that of the center of pressure, but this is impossible 85 in practice because the bearing surfaces must have substantial areas. Each stand is bored centrally to receive the spindle or pivot 7 which is supported in suitable bearings, and is made slightly conical to give it 90 the necessary strength at the point of attachment to the hub. The lower end of each stand is turned true and may if desired form a guide for the lower end of the annular hub formed in the blade. It is preferable to make this a good fit to exclude water 95 as completely as possible. The space 8

around the stand may be filled with a heavy grease for the same purpose.

The propeller blades 9 are of suitable shape and have the necessary area and pitch to 5 drive the vessel at the required speed, it being assumed of course that the engine has the proper capacity. Each blade has a hub 10 containing a conical bore that closely surrounds the stand at the end adjacent the 10 hub. To the outer end of the hub is secured the pivot 7 by any suitable means, as for example by a screw thread. By turning the pivot on its bearings the pitch of the 15 blade can be increased or decreased at will and also reversed.

In order to adjust the position of the blades the following means are provided. On the inner end of each pivot is rigidly mounted a crank 11 whose pin is connected 20 by a link 12 with a pin or trunnion on the sliding block 13. This block is mounted in guides 15 formed on the hub 1 and is reciprocated by the rod 16, the latter extending through the tail shaft 2 into the engine 25 room or other convenient point in the vessel, where it is attached to suitable means for moving it longitudinally but which permit it to turn freely with the shaft. Access to this block may be had by removing the 30 cover 5. In order to prevent water from working into the hub through the various joints the space not occupied by the moving parts is filled with suitable grease which also acts as a lubricant. As the block moves 35 to and fro it displaces the grease from the chamber on one side of it to that on the other through the passage 17, of which a number may be provided. As the block is moved forward or aft by the rod 16, its 40 movement is communicated by the links 12 to the cranks on the blade spindles or pivots 7 and the latter are turned by an amount and in the direction determined by the block. This movement may be enough to 45 reverse the blades or merely to change the angle of pitch.

Fig. 2 illustrates a construction intended for large engines and vessels. In this case the sliding block 13 which moves the blades 50 is actuated by an electric motor located within the hub of the propeller. This avoids the use of the rod 16 and its shifting mechanism, and substitutes therefor a very simple switch means. Mounted to turn 55 freely in the block is a sleeve or bushing 18 which is provided with end flanges that engage the block and move it axially. The sleeve is threaded internally to form a nut which travels on a screw 19 mounted on the 60 end of the tail shaft 2. The forward end of the sleeve is provided with a gear 20 that meshes with a pinion 21 mounted on a counter shaft 22. On the counter shaft is a gear that meshes with a pinion 23 on the 65 armature of the electric motor 24. By means

of this double reduction gearing a relatively small and high speed motor is enabled to move the propeller blades as desired. I do not limit myself however, to such gearing since occasions may arise where simple gearing will suffice. In this case as in Fig. 1 the parts are so designed and arranged that the thrust or tendency of the blades to turn on their axes when in operation is insufficient to move the sliding block. The motor 70 is mounted on a bracket 25 that is preferably attached to and moves with the sliding block 13. The leads for the motor extend through the hollow tail shaft to slip rings 14 mounted on said shaft but insulated therefrom. Riding on these rings are brushes 26 that are connected to a source of current through conductors 27, and a reversing switch 28, the blades of which are shown in dotted lines in one of its positions. As the motor armature revolves in one direction or the other, as determined by the switch, it revolves the sleeve or nut 18 on the screw 19 thereby moving the sliding block and with it the 80 blades, as described in connection with Fig. 1. The chamber within the hub 1 is filled with suitable grease to keep out the water and also to lubricate the parts. The movements of the block cause the grease to pass 85 through the passages 17 from one side thereof to the other. Mounting the motor on the block results in a mechanical simplification of the apparatus as a whole, and affords an arrangement which is extremely simple to 90 construct and keep in order. As it is customary to overhaul vessels at certain intervals, the blades and their adjusting means can be looked after at the same time and the 95 grease renewed.

In order to indicate the position of the propeller blades, an arrangement such as is shown diagrammatically in Fig. 3 may be employed. Mounted on the sliding block 13 and insulated therefrom is a circuit closer 100 30 which at the rear position of the block engages two stationary contacts 31 carried by some part of the hub. These are connected by wires 32, leading through the tail shaft to an electrically actuated indicator 110 115 33 of any suitable construction located at any convenient or desirable place within the vessel. A similar set of contacts 35 is arranged to indicate when the block has reached the forward end of its travel. If 120 it be desired to indicate intermediate positions of the sliding block and hence of the blades, other and similar contacts may be provided and set at intermediate points.

In accordance with the provisions of the 125 patent statutes, I have described the principle of operation of my invention, together with the apparatus which I now consider to represent the best embodiment thereof; but I desire to have it understood that the 130

apparatus shown is only illustrative, and that the invention can be carried out by other means within the scope of the appended claims.

5. What I claim as new and desire to secure by Letters Patent of the United States, is,—

1. In a reversible screw propeller, the combination of a hub having stands projecting outwardly therefrom to substantially the 10 center of hydraulic pressure region of the blades, blades mounted thereon and arranged to be angularly adjusted, each blade being supported on a stand at substantially its center of hydraulic pressure region, spindles that are supported by the stands, each of which is attached to a blade, and means located within the hub for turning the spindles and blades.

2. In a reversible screw propeller, the combination of a hub having stands thereon, each of which extends outwardly therefrom, blades pivotally mounted on the stands, bearings for the blades, the bearings and the outer ends of the stands being located 25 at substantially the center of pressure region of the blades, and means located within the hub for turning the blades angularly about their axes.

3. In a reversible screw propeller, the combination of a hub having stands projecting outwardly therefrom to substantially the center of pressure region of the blades, blades having hubs which receive the stands and are supported thereby, pivots that are secured to the blades and pass 30 through the stands into the hub, actuators attached to the pivots, and means common to the actuators for moving them to change the positions of the blades.

4. In a reversible screw propeller, the combination of a hub having stands projecting outwardly therefrom to substantially the center of hydraulic pressure region of the blades, blades, pivots for the blades 40 mounted in the stands and supported thereby at substantially the center of the hydraulic pressure regions of the blades, a sliding block within the hub, cranks attached to the pivots and connected to the block, and 45 means for moving the block to and fro.

5. In a reversible screw propeller, the

combination of a hollow hub having stands projecting outwardly therefrom to substantially the center of pressure region of the blades, blades mounted thereon, pivots for 55 the blades that extend through the stands into the hub, a sliding block, means for transmitting movements of the block to the pivots to turn the blades, and an electric motor for moving the block forward and 60 backward.

6. In a reversible screw propeller, the combination of a hollow hub having stands projecting outwardly therefrom to substantially the center of pressure region of the 65 blades, blades mounted thereon, pivots for the blades that extend into the hub, a sliding block located in the hub, motion transmitting connections between the pivots and block, a nut and screw for moving the block, 70 and an electric motor for imparting relative movements to the nut and screw to move the blades.

7. In a reversible propeller, the combination of a hollow hub having stands projecting therefrom to substantially the center of pressure region of the blades, blades mounted thereon, pivots for the blades that extend through the stands into the hub, a sliding block which has fore and aft movement in 80 the hub, means for converting the reciprocating movements of the block into oscillating movements of the blades, a nut and screw for moving the block, and an electric motor carried by the block for causing relative 85 rotary motion of the nut and screw.

8. In a reversible screw propeller, the combination of a hub having stands projecting outwardly therefrom to substantially the center of pressure region of the blades, 90 blades mounted thereon, means extending through the stands for moving the blades angularly, an actuator for the means located within the hub, an electric indicator adapted to be located aboard the vessel, and means 95 within the hub for controlling the circuit of the indicator to cause the indicator to show the position of the actuator.

In witness whereof, I have hereunto set my hand this 4th day of June, 1915.

ANATOL DAVID ISKOLS.
